FOREIGN PATENT DOCUMENTS

CA	2307408	11/2001

Primary Examiner—Philip S. Hyder

(74) Attorney, Agent, or Firm—Fitzpatrick, Cella, Harper & Scinto

(57) **CLAIM**

The ornamental design for a multi-application wood working knife, as shown and described.

DESCRIPTION

FIG. 1 is a top perspective view of a multi-application wood working knife showing our new design;

FIG. 2 is a bottom perspective view thereof;

FIG. 3 is a broken bottom view thereof;

FIG. 4 is a broken top view thereof; and,

FIGS. 5 and 6 are end views thereof.

The knife is shown fragmentarily to indicate indeterminate length.
